(57) **CLAIM**

The ornamental design for a pad for a 3D printer pen, as shown and described.

DESCRIPTION

FIG. 1 is a perspective view of a pad for a 3D printer pen. FIG. 2 is a front view of a front side of the pad for a 3D printer pen.

FIG. 3 is a back view of a back side of the pad for a 3D printer pen.

FIG. 4 is a first side view a first side of the pad for a 3D printer pen.

FIG. 5 is a second view of a second side of the pad for a 3D printer pen.

FIG. 6 is a first end view of a first end of the pad for a 3D printer pen.

FIG. 7 is a second end view of a second end of the pad for a 3D printer pen.

FIG. 8 is a cross-sectional view taken along line 8-8 in FIG. 2 of the pad for a 3D printer pen; and,

FIG. 9 is another cross-sectional view taken along line 9-9 in FIG. 3 of the pad for a 3D printer pen.

1 Claim, 5 Drawing Sheets
